UNITED STATES PATENT OFFICE

EARL E. BERRY, OF BELOIT, WISCONSIN, ASSIGNOR TO BELOIT IRON WORKS, OF BELOIT, WISCONSIN, A CORPORATION OF WISCONSIN

STEAM JOINT

Application filed June 9, 1924. Serial No. 719,011.

My invention relates to steam joints, and particularly to steam joints between revolving paper driers and supply lines.

One of the objects of the invention is to provide a tight and advantageous steam joint of the class specified.

Another object of the invention is to arrange for the effective lubrication of the same, and at the same time to avoid the use of oil for lubricating purposes.

Another object of the invention is to secure a simple and practical construction securing such lubrication.

In the accompanying drawings, Fig. 1 is a longitudinal section of a steam joint embodying my invention, the same being employed in connection with a drying cylinder for paper machines;

Fig. 2 is a similar view of a modified form of construction.

Referring to the drawings, and particularly to Fig. 1, I show a rotary paper drier or drying cylinder 1, particularly adapted for use in paper making machines, and an inlet 2 for the steam, and also show a steam supply pipe 3 running to the inlet 2 so that steam may enter the chamber 4 of the latter and pass thence into the chamber 5 of the drying cylinder. The cylinder 1 rotates relatively to the inlet 2 and in accordance with my invention, I provide a joint device or connection such as a packing ring 6 between the cylinder 1 and inlet 2, and this packing ring 6 is composed of material which will make a tight joint between the two members, and also lubricate the same.

I find such a material to be either carbon or graphite or some composition of one or the other, or some material impregnated with one or the other. Such a joint device or packing ring so composed will permit relative rotation between the two members and will also lubricate them by reason of the lubricating qualities of the carbon or graphite.

As a preferred arrangement the packing ring 6 is made with one flat face 7 which comes in contact with the outer face of the flange 8 on the drier 1 and also with a curved or convex surface 9 contacting with a correspondingly curved or convex surface 10 on

the flange 11 on the inlet 2. This arrangement permits a relative angular movement of the cylinder 1 relatively to the inlet 2, and at the same time maintains the tightness of the joint.

A drain pipe 12 is also shown and this passes from the interior of the cylinder 1 through a central supporting member 14 arranged in the interior of the inlet 2. This member 14 is preferably tubular so as to accommodate the inlet pipe 12 and is preferably cast on a cross partition or wall 15 integral with the cylindric wall of the inlet 2. The pipe 12 is extended through the member 14 and provided with an opening 16 opening into chamber 17 formed at the end of member 2 by partition 15, and an outlet drain pipe 18 is connected with chamber 17 so as to receive the water drained through pipe 12.

The member 2 is provided with a head 19 to which the pipe 12 is secured as by bolt 20, and a spring 21 is provided and arranged to fit in a recess or socket 22 in head 19. Spring 21 has its outer end fitted against an abutment 23 on tubular member 24 which is fitted into a ring or collar 25 on an upright tubular support 26.

By this arrangement the spring 21 presses against head 19 of inlet member 2 and therefore has the effect of forcing member 2 against packing ring 6 and the latter against cylinder head 8, and thereby maintains a tight joint.

Thus it will be seen that the drier is provided with a tight joint which automatically lubricates itself without the use of oil, and which also permits twisting or angular movement of the drier relatively to the inlet. It will also be seen that the wear of the packing ring forming the joint is automatically taken up and that when this wear becomes considerable, a new packing ring may be put in place, thereby making it unnecessary to supply a new drier or inlet or parts thereof.

In the construction shown in Fig. 2, the drier 1 and inlet 2 are provided with an inlet packing ring 6 as in the previous arrangement, and the steam pipe 3 is as before, together with the drain pipe 12 and outlet drain 18.

The arrangement shown in Fig. 2, however, differs in that it has means for equalizing the pressure in the drier 1 and inlet 2, so that that pressure will not vary as the steam pressure varies, as is the case in the arrangement of Fig. 1. This arrangement conveniently comprises a diaphragm 30 located at the end of inlet 2, being conveniently held in position by ring 31 secured to the end of inlet 2 by bolts 32-32, which also hold head 19^a of inlet 2 in place. A by-pass duct or passage 33 is provided in inlet 2, connecting chamber 4 with chamber 34 formed at the end of inlet 2. Thus steam pressure will be exerted on diaphragm 30 in a direction opposite to that in which it is exerted in drier 1, and therefore the pressure on the opposite sides of packing ring 6 will be equalized. A spring 35 is preferably provided and located in socket 22 in head 19, and this spring 35 has its outer end acting against a disk 36 carried by diaphragm 30 and secured thereto by another disk 37 and bolt 38 extending to plate 40 secured to collar 25^a on member 26. Thus pressure is exerted by spring 35 tending to form and maintain the steam joint tight.

It will be understood that changes and modifications may be made without departing from the spirit of the invention.

30 What I claim is:

1. The combination with a rotary steam drier and an inlet therefor, of a joint between the same comprising a joint device composed in whole or in part of carbon or graphite.
- 35 2. The combination with a rotary steam drier and an inlet therefor of a packing ring interposed between said drier and inlet and forming a joint between the same, said packing ring being composed in whole or in part of carbon or graphite.
- 40 3. The combination with a rotary steam drier and an inlet therefor, of a joint between the same comprising a joint device made in whole or in part of carbon or graphite, said device having a curved surface permitting angular movement between said drier and inlet.
- 45 4. The combination with a rotary steam drier and an inlet therefor of a joint device for said members made in whole or in part of graphite, and spring means tending to exert pressure to produce and maintain a tight joint.
- 55 5. The combination with a rotary steam drier and an inlet therefor of a joint device for said members made in whole or in part of graphite, and springs means tending to exert pressure to produce and maintain a tight joint, said spring means being at the end of 60 the inlet.
6. The combination of a rotary steam drier and an inlet therefor of a carbon or graphite material joint device between said members and means for equalizing the steam pressure 65 on the opposite sides of said joint or device.
7. The combination of a rotary steam drier and an inlet therefor of a carbon or graphite material joint device between said members and means for equalizing the steam pressure on the opposite sides of said joint or device, 70 said equalizing means comprising a diaphragm on the inlet and means for permitting the steam to act upon said diaphragm in a direction opposite the direction it acts in the drier. 75
8. The combination of a rotary steam drier and an inlet therefor, of a carbon or graphite material joint device between said members and means for equalizing the steam pressure on the opposite sides of said joint or device, 80 said equalizing means comprising a diaphragm on the inlet and means for permitting the steam to act upon said diaphragm in a direction opposite the direction its acts in the drier, said means comprising a duct extending from the inlet chamber of the inlet to 85 said diaphragm.
9. The combination of a rotary steam drier and an inlet therefor, of a carbon or graphite material joint between said members, means 90 for maintaining said joint tight and a drain pipe passing centrally through said inlet communicating with a drain outlet extending from the inlet.
10. The combination of a rotary steam drier and an inlet therefor, of a carbon or graphite material joint between said members, means for maintaining said joint tight and a drain pipe passing centrally through 95 said inlet communicating with a drain outlet 100 extending from the inlet, said inlet being provided with a central tubular supporting member for said drain pipe.
11. The combination of a rotary steam drier and an inlet therefor, of a carbon or graphite material joint between said members, means for maintaining said joint tight and a drain pipe passing centrally through 105 said inlet communicating with a drain outlet 110 extending from the inlet, said inlet being provided with a central tubular supporting member for said drain pipe, and also with a supplemental chamber into which said drain pipe opens and from which a drain outlet extends. 115
12. The combination of a rotary steam drier and an inlet therefor, of a carbon or graphite material joint device interposed between said members and spring means forming a tight joint, said spring means being 120 provided at the rear end of the inlet member and fitted in a socket in the head thereof, and a support for the outer end of said spring means.
13. The combination with a rotary drier 125 and an inlet therefor of a joint between the same comprising a joint device composed of self lubricating material.
14. The combination with a rotary steam drier and an inlet therefor of a ring inter- 130

posed between the drier and inlet and forming a steam joint between the same, said ring being composed of self lubricating material.

15. The combination with a rotary steam drier and an inlet therefor, of a ring composed of self lubricating material and interposed between the drier and the inlet and forming part of the steam pressure between said drier and inlet.

10 In witness whereof, I hereunto subscribe my name this 31st day of May, A. D. 1924.

EARL E. BERRY.

CERTIFICATE OF CORRECTION.

Patent No. 1,769,905.

Granted July 1, 1930, to

EARL E. BERRY.

It is hereby certified that error appears in the printed specification of the above numbered patent requiring correction as follows: Page 3, line 8, claim 15, for the word "pressure" read passage; and that the said Letters Patent should be read with this correction therein that the same may conform to the record of the case in the Patent Office.

Signed and sealed this 21st day of October, A. D. 1930.
